UNITED STATES PATENT OFFICE.

WILLIAM HINGE, OF KENOSHA, WISCONSIN, ASSIGNOR TO THE BADGER
BRASS MANUFACTURING COMPANY, OF SAME PLACE.

ACETYLENE-GAS GENERATOR.

SPECIFICATION forming part of Letters Patent No. 663,169, dated December 4, 1900.

Application filed April 18, 1900. Serial No. 13,299. (No model.)

To all whom it may concern:

Be it known that I, WILLIAM HINGE, of Kenosha, in the county of Kenosha and State of Wisconsin, have invented certain new and useful Improvements in Acetylene-Generators, of which the following is a specification.

This invention relates to improvements in acetylene-generators of that type in which the generating liquid is supplied to the carbid in 10 a substantially continuous flow regulated or in part regulated and controlled by the pressure of gas generated, and refers more specifically to an improved liquid-distributing mechanism for properly regulating and distributing the flow to insure a uniform and efficient generation.

The object of the invention is to provide a construction in which the internal or back pressure of the generated gas acts most efficiently to regulate the control or inflow of liquid, to so construct and arrange the supply-duets that the supply of liquid will be substantially unaffected by the heat of generation, thereby preventing the vaporization 25 of the liquid before it reaches the body of carbid and enabling the generation to be properly localized, and in general to provide a simple, efficient, and inexpensive construction of the character described.

To the above ends the invention consists in the matters hereinafter described, and more particularly pointed out in the appended claims, and will be readily understood from the following description, reference being had 30 to the accompanying drawing, wherein the single figure represents an ordinary velocipede-lamp equipped with my invention, the generator of the lamp and the principal feature of the liquid-distributing mechanism being shown in axial section.

Referring to the drawing, 1 designates the generating-chamber, which so far as the present invention is concerned may be of any usual type adapted to contain a body of carbid, (indicated at 2.)

3 designates a liquid-supply reservoir elevated above the generating-chamber—in the present instance by being mounted upon the rear end of the headlight or flame chamber 4—50 and 5 designates a supply pipe or duct leading from the lower part of the liquid-reser-

voir through and into the upper portion of the generating-chamber and communicating with a distributing-chamber, (designated as a whole by 6.) The supply-pipe 5 is desirably 55 provided with a controlling-cock 7, for convenience of access located outside of the generating-chamber, whereby the flow of liquid to the generating-chamber may be cut off at will, and may also be partially regulated by restricting the flow through the said pipe.

Describing now more particularly the peculiar construction and arrangement of the distributing-chamber, which constitutes the essential feature of novelty of the present invention, said device, as shown, comprises an elongated receptacle, preferably made tapering or conical from a point intermediate of its length upwardly and downwardly toward each end and circular in cross-section, the 70 lower end terminating in a conical point 8, while the upper end 9 communicates with the supply-pipe 5. The distributing-chamber is completely closed, except for the inlet at its point of communication with the supply-pipe 75 and an outlet-opening 10, arranged to extend through its upper conical wall portion a short distance below its juncture with the supply-pipe.

11 designates a coil of pipe, hereinafter termed the "pressure-coil," located entirely within the distributing-chamber and arranged vertically therein, the upper end 12 of said pipe communicating with the outlet-passage 10 of the distributing-chamber, while 85 the lower end 13 of the coil is arranged to communicate with the interior of the distributing-chamber, near the lower end thereof. The main body of the coil consists of horizontally-disposed turns and in the preferred construction shown herein is so shaped as a whole as to conform approximately to the internal formation of the distributing-chamber, but is made sufficiently smaller than the latter in all its dimensions, so that it extends freely within the space of the distributing-chamber and is completely surrounded and jacketed by the liquid when in operation.

In the operation of the device water admitted from the reservoir through the supply-pipe enters and fills the distributing-

chamber and at the beginning of the process of generation also enters the lower end of the pressure-coil, fills the latter, and flows out over the conical outer surface of the distributing-chamber and is by the latter conveyed to the body of carbid, within which it extends. By reason of the peculiar construction of the exterior of the distributing-chamber the liquid will be distributed more or less uniformly over its surface and conveyed to those portions of the charge which rest in immediate contact with its sides. As soon as the pressure in the generating-chamber exceeds the pressure of the hydraulic head, due to the elevated reservoir, the pressure will force back the liquid in the pressure-coil, and by reason of the fact that any given portion of the pressure-coil, except the extreme lower inlet end thereof, is but slightly inclined with reference to a horizontal plane intersecting said portion a relatively large surface area of the liquid contained in said coil will be exposed to the internal pressure of the gas, and the regulation will therefore be extremely sensitive. At the same time the length of the passage through said coil, by reason of its tortuous arrangement, will be relatively great, so that although the liquid will be promptly driven back sufficiently to arrest the escape thereof as soon as the internal pressure exceeds the hydraulic pressure, yet the liquid will not be driven back far enough to permit the gas to escape into the distributing-chamber through the lower end of the coil, and thus permitted to escape into the reservoir except under unusual conditions.

Another feature of importance incident to the construction described is that the liquid in the pressure-coil is jacketed from the internal heat of the generator, so that it reaches the exterior of the distributing-chamber at a relatively low temperature and is therefore not vaporized before it has time to flow over the surface of the latter down into the body of carbid, and it will be further noted that the walls of the distributing-chamber will also be kept relatively cool by means of the liquid within said chamber.

It will be obvious from the foregoing description that the details of construction may be modified to a certain extent without departing from the spirit of the invention, and I do not therefore wish to be limited to these exact details except as they may be made the subject of specific claims.

I claim as my invention—

1. In an acetylene-generator, the combination with a generating-chamber, a source of liquid-supply under pressure and a supply-duct conveying the liquid into the generating-chamber, of means for controlling and distributing the liquid within the generating-chamber, comprising an elongated closed distributing-chamber located within the generating-chamber, arranged to extend at its lower portion into the body of carbid therein and

communicating at its upper portion with the liquid-supply duct, a discharge-outlet located at the upper part of said distributing-chamber and a pressure-coil arranged within the distributing-chamber and surrounded by water therein, and communicating at its upper end with the discharge-outlet thereof, the intaking end of said coil communicating with the lower portion of the distributing-chamber, as and for the purposes described. 75

2. In an acetylene-generator, the combination with a generating-chamber, a liquid-reservoir elevated with reference to said generating-chamber and a supply-duct leading from the reservoir and extending into the generating-chamber, of means for controlling and distributing the liquid, comprising a distributing-chamber provided with a conical lower end portion arranged to extend into the body of carbid and communicating at its upper end with the supply-pipe leading from the reservoir, a discharge-outlet located in the upper part of said distributing-chamber and arranged to discharge the liquid upon the conical exterior thereof, and a pressure-coil arranged within the distributing-chamber and communicating at its upper end with the discharge-outlet, the upper portion of said coil consisting of approximately horizontally-disposed coils and the lower intaking end being arranged to communicate with the interior of the distributing-chamber near the bottom thereof, as and for the purposes described. 100

3. In an acetylene-generator, the combination with a generating-chamber, a liquid-reservoir elevated with reference to said generating-chamber and a supply-duct leading from the reservoir and extending into the generating-chamber, of means for controlling and distributing the liquid, comprising a distributing-chamber provided with a conical lower end portion arranged to extend into the body of carbid and communicating at its upper end with the supply-pipe leading from the reservoir, a discharge-outlet located in the upper part of said distributing-chamber and arranged to discharge the liquid upon the conical exterior thereof, and a pressure-coil arranged within the distributing-chamber and communicating at its upper end with the discharge-outlet thereof, said coil comprising a plurality of horizontally-disposed turns and being formed to conform as a whole approximately to the internal shape of the distributing-chamber, but of smaller size in all its dimensions than the corresponding dimensions of the distributing-chamber, so as to be insulated by the liquid of the distributing-chamber from the heat of the generating-chamber and arranged to communicate at its lower end with the lower portion of the distributing-chamber, substantially as and for the purposes described. 115

WILLIAM HINGE.
